DESIGN FOR A GOLF BALL OR THE LIKE

Frank H. Cavignac, New York, N. Y., assignor to
Mervin P. Doughty, Lawrence, N. Y.

Application April 5, 1937, Serial No. 68,571

Term of patent 14 years

To all whom it may concern:

Be it known that I, Frank H. Cavignac, a citizen of the United States of America and resident of New York city, county of Queens, and State of New York, have invented a new, original, and ornamental Design for Golf Balls or the like, of which the following is a specification, reference being had to the accompanying drawing, forming part thereof.

In the drawing:

Figure 1 is an elevational view of a golf ball showing my new design.

Figure 2 is an elevational view of the golf ball shown in Figure 1 after the same has been rotated to the left through approximately 40° in a horizontal plane.

Figure 3 is a fragmentary sectional view taken along the line 3—3 of Figure 2.

I claim:

The ornamental design for a golf ball or the like as shown.

FRANK H. CAVIGNAC.
